UNITED STATES PATENT OFFICE.

EDWARD L. FONSECA, OF NEWARK, NEW JERSEY, ASSIGNOR TO THE WILCOLATOR COMPANY, OF NEWARK, NEW JERSEY, A CORPORATION OF DELAWARE.

QUICK-ACTING CONTROL MECHANISM.

Application filed June 19, 1926. Serial No. 117,181.

This invention relates to control mechanisms and is concerned more particularly with a control device which is capable of exerting a powerful force so that it may 5 operate a valve, damper, or the like with a quick action, but which is capable of being brought into action by a weak force, so that it may be made highly sensitive.

Control devices of this type are of especial utility in connection with heating devices in which it is desired to shut off the supply of fuel quickly when a predetermined temperature is reached, as, for example, in the chamber being heated. For that purpose, the device is used in conjunction with an element which is responsive to temperature and assumes different positions as temperature variations occur. Such elements, when sufficiently sensitive to permit 20 an exact temperature control are ordinarily of a delicate construction and are incapable of exerting the force required to close a heavy valve, especially when the movable part of the valve is liable to stick owing 25 to accumulations of tar or other impurities from the fuel. Also, such an element is not ordinarily capable of directly releasing the latch of a valve of the self-closing type when the valve is weighted by a spring 30 heavy enough to insure quick and positive action.

In some instances these heating devices are to be operated for definite periods of time, in which event, a clock mechanism is employed for the purpose of controlling the supply of fuel, but here again the force which this clock mechanism is capable of exerting is not always sufficient to close the fuel supply valve, or to release the latch of 35 a self-closing valve.

The object of the present invention is to provide a control mechanism of the quick-acting type which is so constructed and arranged that it may be actuated by a delicate 40 temperature-responsive element or clock mechanism and when brought into action exerts a relatively powerful force capable of performing the desired function of closing a fuel supply valve, damper, or 45 the like. In this mechanism, is included a latch device having two stages which are brought into operation successively with a brief time interval. A shaft weighted by a powerful spring is arranged for operative 50 connection to a valve, etc., and this shaft

may be set by a handle to open the valve. The shaft is held in this position by a major latch, and a considerable force is required to release this latch so that the heavy spring 60 can rotate the shaft to close the valve. This force is exerted by a spring-actuated hammer, ordinarily held out of action by a minor latch device, which requires but little force to release it and is thus capable of 65 operation by a thermostatic element or a clock mechanism. When the heating has continued until a definite temperature has been reached in the oven chamber, or a definite period of time has elapsed, the thermostatic element or the clock mechanism 70 operates to release the minor latch. This frees the hammer which at once moves to release the major latch, thus permitting the heavy spring to close the valve through the working connections. The valve now 75 remains closed until the device is again set by the handle, in which action both latches are rendered effective ready for release when the proper conditions recur.

For a better understanding of the invention, reference may be had to the accompanying drawings, in which there is shown one embodiment suitable for the control of a gas heater. In these drawings,

Fig. 1 is a lay-out of the mechanism with the parts shown somewhat diagrammatically,

Fig. 2 is a face view of the latch device with the cover plate removed,

Fig. 3 is a section on the line 3-3 of Fig. 2,

Fig. 4 is a side view of a temperature-responsive device which may be used with the new controller, and

Fig. 5 is a perspective view of certain of the parts shown in Fig. 4.

Referring now to the drawings, the device is illustrated in the form in which it may be used to control the temperature in a gas oven provided with burners supplied with gas through a pipe line 10. In this line is a valve 11 of any standard type, provided with an operating handle 12. This handle is connected by a link 13 to an arm 14 mounted on the shaft 15 of the latch device. A heavy spring 16 encircles the shaft 15 and is secured to the shaft at 17, the other end of the spring being secured to a post 18 extending from the housing 19 through which the shaft extends. The spring 16 ex-

erts a force which tends to keep the valve 11 closed, and when this spring is released, the valve snaps closed with a rapid action and the spring is of sufficient strength to prevent the valve sticking open, due to the accumulation of tar or other impurities in the gas.

The housing 19 which contains the latch mechanism, may be mounted at any convenient point on the heater or adjacent thereto. This housing is cup-shaped and provided with a cover plate 20, through which extends the shaft 15. On the end of the shaft which projects through the cover plate is a setting handle 21 and the housing is provided with a hollow boss 22, in which is threaded a pipe 23 leading to the temperature-responsive device, generally designated 24.

Pivottally mounted at 25 within the housing, is a dog 26, the tail of which carries a lug 27 through which projects the end of a rod 28, which extends through the pipe 23. The rod is connected to the lug 27 in any convenient manner, as, for instance, by means of cotter pins 29 passing through holes in the rod and lying on either side of the lug. The dog is forced to swing in a counter-clockwise direction on its pivot, as seen in Fig. 2, in any convenient manner, as by means of a light spring 30 secured at one end to the dog and bearing at the other against the wall of the casing. At its end the dog has a projecting tooth 31 which engages a projection 32 on a hammer 33. The hammer 33 is mounted loosely on a tubular projection 34 extending from one face of a plate 35 fixedly secured to the shaft 15 within the housing, and a light spring 36 secured at one end to a screw 37 threaded into the shaft and at the other bearing against a pin 38 projecting from the face of the hammer 33, tends to force the hammer 33 in a counter-clockwise direction about the shaft 15 as a center.

The plate 35 is provided with a shoulder 39 in its rim and this shoulder may be engaged with a tooth at the end of a dog 40 pivotally mounted at 41 within the housing. The dog has a tail 42 provided with an up-standing lug 43 and a light spring 44 connected to the tail and to a pin 45 in the face of the housing, normally tends to swing the dog so that the tooth will bear against the rim of the plate 35. The pin 38 in the hammer 33 has an extension 46 lying beyond the rear face of the hammer and in the path of the shoulder 39. A nut 46' threaded on the shaft 15 holds the hammer 33 in position against the plate 35, which, in turn, bears against a washer 46" interposed between the plate 35 and the inner face of the housing, the spring 16 forcing the shaft in a direction such that the nut 46' holds the plate 35 in firm contact with the washer 46".

The pipe 23 leads to a housing 47 into which the end of the rod 28 projects, and

within the housing is a swinging arm 48 secured on a shaft 49 which extends rearwardly from the housing and lies within a tube 50. To the rear end of the shaft is secured an arm 51 provided with a pin 52 which enters a slot 53 in an L-shaped bracket 54 mounted on the end of a bi-metallic thermostatic strip 55 the other end of which is secured to a stirrup 56 pivotally mounted on a pin 57 which lies in an aperture in a block 58 projecting from the rear face of the housing 47. Within the housing is a boss 59 in which is mounted a screw 60 carrying a cup-shaped dial 61 on its outer end, this dial closing the front end of the housing 47 and on its rim, as at 62, having graduations indicating degrees. A fixed pointer 63 on the housing cooperates with the dial and provides means for setting the device for any temperature. The adjustment of the dial causes the screw 60 to move in or out of the boss 59 and at its rear end the screw presses against an abutment 64 secured to the stirrup 56. The movement of the screw causes the stirrup to swing about the pin 57 and this in turn adjusts the other end of the thermostatic strip with reference to the pin 52. By the proper adjustment of the dial, the thermostatic strip may be set to produce a swinging movement of the arm 51 at any temperature within the temperature range of the device, and when the arm 51 is moved by the warping of the thermostat resulting in the movement of the end of the thermostat which carries the bracket 54, this arm causes shaft 49 to rock and the arm 48 bears against the end of the rod 28, and moves it lengthwise. The details of construction of the thermostatic mechanism form no part of the present invention, and are shown in my co-pending application, Ser. No. 48,501, filed August 6, 1925. This device is merely one convenient form of an adjustable temperature-responsive mechanism which may be used with the new latch mechanism.

In the operation of the new controller, the thermostatic element is set to cause a movement of the rod 28 at any selected temperature by the adjustment of the dial 61. In the cold position of the thermostatic strip, the arm 48 lies in a position which permits the spring 30 to swing the dog 26 on its pivot, at the same time moving the rod 28 to the right, as shown in Fig. 1. The dog takes a position in which its tooth 31 lies in the path of the tooth 32 on the hammer 33, the normal position of the hammer when the device is released being such that the two teeth are in opposition but spaced apart slightly. The latch mechanism is now set manually by means of the handle 21 which is moved to turn the shaft 15 counter-clockwise. During this setting action, the hammer 33 is moved to bring its tooth 32 into engagement with the dog 26, while the plate 35 is moved

until the shoulder 39 thereon rides behind the tooth on the dog 40. This movement of the shaft is against the pressure of the heavy spring 16, and when the handle is released, the shaft is held against being moved by the spring due to the engagement of the shoulder 39 with the dog 40. The setting movement of the shaft is transmitted through the linkage to open the valve 11 and fuel flows to the oven burners through the valve. When the temperature for which the device is set to operate is exceeded, the warping of the thermostatic strip causes movement of the shaft 49 which swings arm 48, causing it to move the rod 28 longitudinally. This movement unlatches the dog 26 from the hammer 33 and the hammer 33 is now swung about the shaft 15 by the action of the light spring 36. A projection 64 near the end of the hammer now strikes the projection 43 on the dog 40 with a sharp blow, swinging the dog on its pivot 41 to an extent sufficient to release the plate 35. The shaft 15 is now free to be moved by the heavy spring 16 and as the shaft rotates, it closes the valve 11 by means of the linkage 12, 13, 14. As the shaft is rotated in a clockwise direction by the spring 16, it carries with it the plate 35 and the shoulder 39 on the plate bears against the projection 46 on the rear face of the hammer 33, moving the dog until its end 64 strikes a stop pin 65 projecting from the rear wall of the housing. In this position of the hammer 33, its tooth 32 lies slightly beyond the tooth 31 on the end of the dog 26, and when the handle 21 is again moved to set the device, the initial movement of the shaft and the plate 35, permits the hammer 33 to be moved slightly away from the stop pin 65 by its spring 36, this movement continuing until the tooth 31 on dog 26 is engaged with the tooth 32 on the hammer, after which the hammer remains stationary. The further movement of the shaft by the handle moves the plate 35 to a position in which its shoulder 39 rides past the tooth on the dog 40. The setting movement of the handle is limited by the engagement of a shoulder 67 on the plate 35 contacting with a stop pin 66 projecting from the rear wall of the housing. It will be noted from the foregoing that the manual setting of the device renders both latch devices effective.

55 The latch mechanism includes the four springs 30, 36, 44, and 16, and the first three springs are relatively light, while the latter is a heavy spring. The spring 30 is the lightest of the group, so that but little resistance is offered to the movement of the rod 28 effected by the arm 48. The dog 26 and hammer 33 form the minor latch device, while the dog 40 and the plate 35 form the major latch device. It will be observed that 60 the latch mechanism operates in two stages, the two latch devices being released-successively with a brief time interval. The release of hammer 33 by the movement of dog 26 resulting from a longitudinal movement of the rod 28, permits hammer 33 to be swung about the shaft by means of the light spring 36, and when the hammer has moved through an arc of approximately 90°, it strikes the tail of dog 40, and causes this dog to release the plate 35 secured rigidly to the shaft. By this relay construction, it is possible to provide a mechanism which is sensitive in operation, since it may be brought into action by light forces exerted by a temperature-responsive element. At the same time, the valve-closing mechanism may be sufficiently powerful to close the valve with a rapid action when released.

65 It will be noted that with the new controller the thermostat and the latch mechanism may be constructed as a rigid assembly unit, the thermostat being carried in a housing which is rigidly mounted on the end of the pipe leading to the housing for the latch mechanism, through which pipe extends the operating rod. By rigidly mounting the thermostat with reference to the latch device, permanence of calibration is secured. The device may be adjusted at the factory for the conditions under which it is to be used, and may then be mounted at any convenient point on the heater, or near the heater. In thus mounting the device, the calibration of the adjusting means for the thermostatic element is not changed. It will further be observed that the shaft 15 is connected by linkage to the fuel supply valve or to a damper or some other control element, and by such a flexible connection it is possible merely by changing the length of the links or by adding additional links, to connect the mechanism to operate the control element at any convenient point. Also, the device may be used to operate two control elements, as, for example, both a valve and a damper. It is not necessary that the operating spring 16 should be mounted on the shaft 15 and in some instances it may be desirable to connect this spring to the arm 14 or to some member of the linkage connection with the other end of the spring secured to any rigid point.

70 With the new controller it is impossible to lock the valve or control element open, once the thermostatic element has tripped the mechanism as the mechanism cannot be reset manually until normal conditions have been restored. This is due to the fact that so long as the selected temperature is exceeded, the thermostatic element will hold the push rod 28 in a position such that the dog 26 will be rendered ineffective, and any attempt to reset the mechanism by the handle 21 will be fruitless as the major latch will be inoperative. This is because the hammer 33 is 75

75 80 85 90 95 100 105 110 115 120 125 130

65 70 75 80 85 90 95 100 105 110 115 120 125 130

held by its spring 36 in a position in which the pin 46 bears against the shoulder 39 and when the handle is turned to move the shaft 15 counterclockwise, the hammer 33 follows 5 the plate as the latter moves and the projection 64 on the hammer engages the tail 43 on dog 40 and swings this dog to a position 10 in which its tooth is clear of the shoulder 39. This action of the hammer is such that 15 the dog 40 is held inoperative and therefore cannot hold the plate 35 in set position. When the thermostat is restored to its normal position by the temperature falling below the predetermined point, the dog 26 will 20 lie in a position to engage the tooth 32 of the hammer and then when the handle is moved, the dog 40 will ride over the shoulder 39 on the plate 35 and hold the plate and shaft against return movement. The 25 device thus insures that the heater will not be supplied with fuel when a predetermined temperature has been exceeded. As soon as this temperature is reached, the thermostatic element will release the two stage latch mechanism and cause the fuel supply valve to be closed, and the valve cannot be held open by the device until the temperature in the heating chamber has fallen below the 30 critical point.

While I have shown the new control mechanism arranged to operate a valve, it is evident that it may be used to operate a damper or some other control device of this character. Similarly, the device may be brought 35 into action by a clock mechanism, instead of a temperature-responsive device.

I claim:

1. In control mechanism of the type described, the combination of a rotatably 40 mounted shaft, means tending to hold the shaft in one position, a handle for moving the shaft to a second position, a latch device operable to hold the shaft in its second position, releasing means for this latch device, 45 a second latch device for holding the releasing means out of action, both latch devices being rendered effective when the shaft is moved to its second position by the handle, and means for releasing the second latch device.

2. In control mechanism of the type described, the combination of a rotatably mounted shaft, a spring tending to hold the shaft in one position, a handle connected to the shaft by which the shaft may be moved to second position, a latch device effective to hold the shaft in its second position, a spring-actuated hammer mounted for free movement on the shaft and movable by its 55 spring to a position in which it renders the latch device ineffective, a second latch device for holding the hammer out of operation, and means for releasing the second latch device.

3. In control mechanism of the type de-

scribed, the combination of a rotatably mounted shaft, a spring tending to hold the shaft in one position, a handle connected to the shaft by which the shaft may be moved to second position, a latch device effective to hold the shaft in its second position, a hammer freely mounted on the shaft, a spring for forcing the hammer in one direction, this hammer being movable by the spring to engage the latch device and render it ineffective, a second latch device for normally holding the hammer out of action, both latch devices being rendered effective by the movement of the shaft by the handle, and means for releasing the second latch device whereby the hammer is moved by its spring to release the first latch device.

4. In control mechanism of the type described, the combination of a rotatably mounted shaft, a spring tending to hold the shaft in one position, a handle connected to the shaft by which the shaft may be moved to second position, a latch device effective to hold the shaft in its second position, a hammer operable to render the latch device ineffective to hold the shaft, means for causing the hammer to perform the said function, a second latch device for holding the hammer in inoperative position, temperature-responsive means, and a connection between the temperature-responsive means and the second latch device whereby this latch device is released when a predetermined temperature is reached.

5. In control mechanism of the type described, the combination of a housing, a shaft projecting into the housing, a spring tending to move the shaft to one position of rest, a handle connected to the shaft by which the shaft may be moved to a second position, a latch device within the housing effective to hold the shaft in its second position, a spring-actuated hammer within the housing movable to render the said latch device ineffective, a second latch device within the housing for holding the hammer in ineffective position, and means entering the housing through a wall thereof for releasing the second latch device whereby the hammer is moved by its spring to release the first latch device.

6. In control mechanism of the type described, the combination of a housing, a shaft projecting into the housing, a spring tending to move the shaft to one position of rest, a handle connected to the shaft by which the shaft may be moved to a second position, a latch device within the housing effective to hold the shaft in its second position, a spring-actuated hammer within the housing movable to render the said latch device ineffective, a second latch device within the housing for holding the hammer in ineffective position, a temperature-responsive element rigidly mounted with relation to the

housing and having a part movable to different positions in accordance with temperature variations, and a connection between the temperature-responsive element and the 5 second latch device for releasing the latter when a predetermined temperature is reached.

7. In control mechanism of the type described, the combination of a housing, a 10 shaft projecting into the housing, a spring tending to move the shaft to one position of rest, a handle connected to the shaft by which the shaft may be moved to a second position, a latch device within the housing 15 effective to hold the shaft in its second position, a spring-actuated hammer within the housing movable to render the said latch device ineffective, a second latch device within the housing for holding the hammer in ineffective 20 position, a temperature-responsive element, a mounting for the element rigidly connected to the housing, and a connection between the element and the second latch device whereby the said latch device is released by the element when a predetermined 25 temperature is attained.

8. In control mechanism of the type described, the combination of a housing, a shaft projecting into the housing, a spring 30 tending to move the shaft to one position of rest, a handle connected to the shaft by which the shaft may be moved to a second position, a latch device within the housing effective to hold the shaft in its second position, a spring-actuated hammer within the 35 housing movable to render the said latch device ineffective, a second latch device within the housing for holding the hammer in ineffective position, a temperature-responsive 40 element having a part movable to different positions in accordance with temperature variations, means for adjusting the action of the said element, and a connection between the movable part of the element and the second latch device whereby the said latch device is released by the action of the element when the latter is exposed to a predetermined 45 temperature.

9. A control mechanism of the type described, which comprises the combination of an element responsive to temperature and having a part which moves to different positions in accordance with temperature variations, a valve for controlling the supply 55 of fuel to a burner, a shaft operatively connected to the valve, a spring tending to hold the shaft in a position in which the valve connected to the shaft is closed, a handle for moving the shaft to a second position in which the valve is open, a latch device for holding the shaft in its second position, a second latch device operable to release the first, and means connecting the second latch device and the said element thereby the 60 movement of the element due to a selected

temperature being reached causes the release of the latch devices successively.

10. A control mechanism of the type described, which comprises the combination of an element responsive to temperature and 70 having a part which moves to different positions in accordance with temperature variations, a valve for controlling the supply of fuel to a burner, a shaft operatively connected to the valve, a spring tending to hold the shaft in a position in which the valve connected to the shaft is closed, a handle for moving the shaft to second position in which the valve is open, a plate rigidly secured to the shaft, a latch device engaging 75 the plate and operable to hold the shaft in its second position, a second latch device for releasing the first, and a connection between the second latch device and the temperature-responsive element operable by the latter to release the second latch device when a predetermined temperature has been reached.

11. In control mechanism of the type described, the combination of a rotatably mounted shaft, a spring tending to hold the shaft in one position, a plate rigidly secured to the shaft, a handle connected to the shaft by which the shaft may be moved to a second position, a latch device engaging the plate and operable to hold the shaft in its second position, a spring-actuated hammer mounted loosely on the shaft and movable relative to the shaft to engage the latch device and render it ineffective, a second latch device for holding the hammer in ineffective position, and means for releasing the second latch device whereby the hammer is moved by its spring to release the said latch device.

12. In control mechanism of the type described, the combination of a rotatably mounted shaft, a spring tending to hold the shaft in one position, a plate rigidly secured to the shaft, a handle connected to the shaft by which the shaft may be moved to a second position, a spring-pressed dog engageable with a notch in the plate and effective to hold the shaft in its second position, a hammer loosely mounted on the shaft and movable by a spring to engage the dog and render it ineffective, a second dog engageable with the hammer to hold it out of action, and means acting on the second dog to release the hammer, whereby the latter is moved by its spring and renders the first dog 105 ineffective.

13. In control mechanism of the type described, the combination of a housing, a shaft entering the housing, a spring tending to hold the shaft in one position, a plate secured rigidly to the shaft within the housing, a handle connected to the shaft by which the shaft may be moved to a second position, a dog within the housing engageable with the plate to hold the shaft in its second position.

tion, a hammer loosely mounted on the shaft and movable by a spring to a position in which it renders the dog ineffective, a second dog engageable with the hammer to hold the latter against movement, the hammer being forced into position for engagement with the second dog by the plate when the shaft is in its first position, and means for rendering the second dog ineffective where-
10 by the hammer is moved by its spring to render the first dog ineffective.

14. In control mechanism of the type de-
scribed, the combination of a housing, a shaft entering the housing, a spring tend-
15 ing to hold the shaft in one position, a plate secured rigidly to the shaft within the housing, a handle connected to the shaft by which the shaft may be moved to a second position, a dog within the housing engage-
20 able with the plate to hold the shaft in its second position, a hammer loosely mounted on the shaft and movable by a spring to a position in which it renders the dog ineffec-
25 tive, a second dog engageable with the ham-
mer to hold the latter against movement, the hammer being forced into position for en-
gagement with the second dog by the plate when the shaft is in its first position, a rod connected to the second dog, and a tem-
30 perature-responsive element operable when a predetermined temperature is reached for moving the rod to cause the second dog to release the hammer.

15. In control mechanism of the type de-
scribed, the combination of a rotatably mounted shaft, a spring tending to hold the shaft in one position, a handle connected to the shaft by which the shaft may be moved to a second position, a latch device effective
40 to hold the shaft in the second position, an element movable through a path of travel de-
fined at one end by the latch device, a sec-
ond latch device for holding the element at the opposite end of its path of travel, means
45 for releasing the second latch device, and means for propelling the element toward the first latch device to engage and render in-
operative said device when the element is re-
leased by the second latch device, the ele-
50 ment being propelled by the said means with great rapidity.

16. In control mechanism of the type de-
scribed, the combination of a rotatably mounted shaft, a spring tending to hold the shaft in one position, a handle connected to the shaft by which the shaft may be moved to a second position, a latch device effective to hold the shaft in the second position, an element movable through a path
55 of travel defined at one end by the latch device, a second latch device for holding the element at the opposite end of its path of travel, means for releasing the second latch device, means for propelling the element to-
60 ward the first latch device to engage and

render inoperative said device when the ele-
ment is released by the second latch device, and means carried by the shaft for engag-
ing the element and restoring it to the other end of its path of travel as the shaft is 70 moved by its spring to its first position upon release of the first latch device.

17. In a control mechanism of the type de-
scribed, the combination of a rotatably mounted shaft, means tending to hold the shaft in one position, a latch mechanism for holding the shaft in a second position, a member movable to release the latch me-
75 chanism, a second latch mechanism for holding the member against releasing movement, the first latch mechanism upon being released being operative to restore the member to its inoperative position, wherein it may be held against movement by the second latch me-
80 chanism, and means for releasing the second 85 latch mechanism.

18. In a control mechanism, the combina-
tion of a rotatably mounted shaft, means tend-
ing to hold the shaft in one position, means for moving the shaft to a second po-
sition, a latch mechanism operable to hold the shaft in its second position, releasing 90 means for this latch mechanism, a second latch mechanism for holding the releasing means out of action, means for returning the 95 releasing means to its inoperative position after the release of the first latch me-
chanism, and means for releasing the second latch mechanism.

19. In control mechanism of the type de-
scribed, the combination of a rotatably mounted shaft, a spring tending to hold the shaft in one position, a handle connected to the shaft by which the shaft may be moved to a second position, a latch device effective 100 to hold the shaft in its second position, a spring actuated hammer held away from the latch device by the shaft when the latter is in its first position, a second latch device for holding the hammer in the said posi-
105 tion, and means for releasing the second latch device, whereby the hammer is moved by the spring to release the first latch device.

20. In control mechanism, the combina-
tion of a rotatably mounted shaft, means tend-
ing to hold the shaft in one position, means by which the shaft may be moved to a second position, a latch device effective 110 to hold the shaft in the said second posi-
tion, means movable to release the latch de-
vice, a second latch device for holding the 115 releasing means out of operation, tempera-
ture-responsive means, and means operated by the temperature-responsive means for 120 rendering the second latch device ineffective when a selected temperature is reached.

In testimony whereof I affix my signature.

EDWARD L. FONSECA.
